Primary Examiner — Calvin E Vansant
Assistant Examiner — Mark T. Philippss

(57) **CLAIM**

The ornamental design for a robotic mower, as shown and described.

DESCRIPTION

1.1: is a top, front, left a perspective view of a robotic mower;

1.2: is a bottom, rear, right perspective view of a robotic mower;

1.3: is a perspective view of robotic mower in an alternate state of use;

1.4: is a front view of the design as shown in 1.1;

1.5: is a back view of the design as shown in 1.1;

1.6: is a left view of the design as shown in 1.1;

1.7: is a right view of the design as shown in 1.1;

1.8: is a top view of the design as shown in 1.1;

1.9: is a bottom view of the design as shown in 1.1.

The broken lines shown in the drawings depict portions of the robotic mower in which the design is embodied that form no part of the claimed design.

1 Claim, 9 Drawing Sheets
